UNITED STATES PATENT OFFICE.

ASHER B. STEVENS, OF STAPLETON, NEW YORK, ASSIGNOR TO THOMPSON,
PERLEY & WAITE, OF BALDWINSVILLE, MASSACHUSETTS.

CHAIR.

SPECIFICATION forming part of Letters Patent No. 270,144, dated January 2, 1883.

Application filed January 7, 1882. (No model.)

To all whom it may concern:

Be it known that I, ASHER B. STEVENS, of Stapleton, county of Richmond, State of New York, have invented an Improvement in Chairs, 5 of which the following description, in connection with the accompanying drawings, is a specification.

This invention in child's chair is an improvement on United States Patent No. 179,851, 10 July 18, 1876, to which reference may be had. In that patent the upper ends of the pivoted legs were each provided with teeth to engage the teeth of the leg co-operating with it, so that the said legs moved in unison, and the separate 15 legs of each pair of legs were of one piece, and the legs were held in adjusted position by a long spring, which like a hook engaged teeth of a rack attached to the lower side of the seat.

The object of my invention is to simplify and 20 cheapen the construction of the chair shown in the said patent and make it more durable. In this my present invention I have divided each leg into two parts, have pivoted one part of each leg upon a depending rigid part of the 25 seat-frame, and above the said pivots I have placed two pinions provided with straps having at their sides studs, one of which is caught at suitable times in one of a series of three notches of a locking device (shown as a catch) pivoted 30 upon the other strap. The outer ends of these straps are connected with the movable side pieces of the pivoted legs.

The particular features constituting my invention will be stated in the claims at the end 35 of this specification.

Figure 1, in full lines, represents in side elevation one of my improved chairs in its most elevated position, the dotted lines showing the seat lowered and the legs turned to form a 40 rocking-chair. Fig. 2, in full lines, is a side elevation of my improved chair in its second position as a high carriage, the seat being lower than in Fig. 1, while the dotted lines show the said seat lowered to its third position to make 45 a lower carriage. Fig. 3 is a detail of the locking device detached, and Fig. 4 is a section of the strap on the dotted line xx to show the stud engaged by the said locking device.

The seat a , arms a' , back a'' , and rigid part

j below the seat, and to which the legs are pivoted, are all as usual. Each leg is composed of a part, b , suitably curved to serve as a rocker, and a part, b' , hinged or pivoted upon it at b^2 . The upper end of part b is pivoted at c to the rigid part j of the seat-frame. The upper end of each part b' is jointed to the end of a metal strap or arm, d , having connected rigidly with it a pinion, e . The pinions e of the straps of the legs at the same side of the seat mesh together, as shown in the drawings. As the legs are 50 turned about their pivots or centers c the parts b' joined with the straps d , move the latter and turn their pinions e about the pivots 2 , both legs thus moving at the same time and in unison. The pinions meshed together as described insure a like extent of movement of the legs about their centers c . Each strap d , connected with the part b' at the rear of the frame j , has a stud, d^2 , cast upon it, (see Fig. 4,) into drilled holes in which is inserted a 55 wrought-metal rivet, d^3 , which will be engaged by the notched parts of the locking bar or latch g , pivoted at 5 upon that strap, d , which is extended from the opposite pinion e , and connected with the leg part b' , located under the 60 front part of the seat-frame. The locking device carried by one strap engages a stud attached to the other strap and holds the said straps in either of the four positions shown in 65 full and dotted lines, Figs. 1 and 2, and consequently locks the leg b at the front and back of the chair-seat in their adjusted positions, to 70 serve either as a high chair, high or low carriage, or as a rocking-chair.

The legs b are and may be supplied with 75 rollers or wheels h , of usual construction. The rollers or wheels may be connected with the legs or with suitable rounds between or to frames secured to the legs, as may be desired.

The notch in the locking bar or brace g near 80 its free end serves to hold the chair-seat and legs in the full-line positions, Figs. 1 and 2, or in two different positions, this being possible owing to the fact that the change of centers from one to the other of the two positions mentioned, although changing the level of the seat a , leaves the pivot 5 and stud d^2 at the same 85 distance apart, but with the stud d^3 and pivot

in different positions in the arc of a circle in which they are moved.

I claim—

1. The seat-frame and pivoted front and rear legs composed of parts $b b'$, and the pinions e , geared together as described, combined with the straps between the said gears and the upper ends of the jointed parts b' of the said legs, substantially as described.
- 10 2. The seat-frame, the front and rear legs composed of parts $b b'$, to support the said seat, the strap g , connected with the parts b' of the said legs, and with the gears meshed together as shown, combined with a hook or catch carried by one strap and adapted to engage a stud connected with the other strap, substantially as described.
- 15 3. The pinions $e e$ to cause the pivoted legs of the chair to turn together in unison, and metal straps extended from and moving with the said pinions, combined with a locking device pivoted upon one of the said straps and

engaging a stud upon the other strap, whereby the legs of the chair are held in their adjusted positions, substantially as described.

4. The pinions $e e$ to cause the pivoted legs of the chair to turn together in unison, and metal straps extended from and moving with the said pinions, combined with a locking device pivoted upon one of the said straps and having three notches, and a stud connected with the other of the said straps, whereby the said legs may be held in four positions, one of the said notches and the said stud holding the said legs in two different positions, substantially as described.

In testimony whereof I have signed my name to this specification in the presence of two subscribing witnesses.

ASHER B. STEVENS.
